(57) CLAIM

The ornamental design for a gift bag with candy dispenser, as shown and described.

DESCRIPTION

FIG. 1 is a perspective view of the gift bag with candy dispenser of the present invention, with closed dispenser.

FIG. 2 is a front view thereof;

FIG. 3 is a rear view thereof;

FIG. 4 is a right side view thereof, the left side being a mirror image;

FIG. 5 is a top view thereof;

FIG. 6 is a bottom view thereof; and,

FIG. 7 is a perspective view thereof, with the dispenser flap shown in an open condition.

The broken line showing is included for the purpose of illustrating environment and forms no part of the claimed design.
